UNITED STATES PATENT OFFICE

GLENN F. COUCH, OF ROCHESTER, NEW YORK, ASSIGNOR TO THE GOULD COUPLER COMPANY, OF DEPEW, NEW YORK, A CORPORATION OF MARYLAND

TRUCK PEDESTAL

Application filed May 5, 1928. Serial No. 275,484.

This invention relates to truck pedestals and more particularly to a reinforced pedestal adapted to receive replaceable wear plates or liners on the jaws thereof.

5 The principal object of my invention, generally considered, is to provide a pedestal of the cast type which is formed with an upper portion adapted for connection with an associated railway truck side frame and depending jaws spaced to receive an associated journal box therebetween with the junctions between said jaws and the connecting portion being reinforced by outstanding flanges or ribs on the inside or outside 10 side or both sides thereof.

Another object of my invention is to provide a pedestal with upstanding spaced flanges adapted to embrace and be connected to the side frame of a railway truck and depending jaw portions at the ends of said flange portions spaced to receive an associated journal box therebetween, the union between said jaw portions and connecting flange portions being rigidified by flanges 25 or ribs outstanding from the lower edges of said connecting portions between the jaw portions and curving downwardly at their ends around the junctions with the jaw portions and extended therealong.

30 A further object of my invention is to provide a wear or liner plate for connection to spaced depending jaws of a truck pedestal, said plate being generally U-shape in section with outwardly extending flanges 35 embracing the associated jaw of the pedestal and riveted thereto, or preferably to outstanding flange portions thereof.

Other objects and advantages of the invention relating to the particular arrangement and construction of the various parts 40 will become apparent as the description proceeds.

Referring to the drawings illustrating my invention, the scope whereof is defined by 45 the appended claims:

Figure 1 is a side elevation, partly in longitudinal vertical section, of a truck pedestal, the associated truck side frame, journal box and equalizer being fragmentarily indicated by dot and dash lines.

Figure 2 is a transverse vertical sectional view on the line 2—2 of Figure 1, looking in the direction of the arrows.

Figure 3 is a fragmentary plan view of the pedestal.

Figure 4 is a horizontal sectional view of one of the jaws of said pedestal on the line 4—4 of Figure 1, looking in the direction of the arrows.

Referring to the drawings in detail, like parts being designated by like reference characters, the truck side frame is diagrammatically indicated by dot and dash lines at 1 and the pedestal is designated by the reference character 2. Said pedestal comprises a pair of upright flanges 3 and 4 adapted to fit on opposite sides of the side frame 1 and be bolted thereto in the ordinary or conventional manner, the front flange 3 being for that purpose provided with holes 5 for the reception of bolts or other connecting means (not shown). The flanges 3 and 4 adjacent their ends are connected by webs 6 which normally abut the underface of the frame 1 and are adapted for connection thereto by bolts or other connecting means extending through apertures 7.

The pedestal 2 is provided with a pair of jaws 8 spaced to receive an associated journal box therebetween indicated by dot and dash lines at 9, the engaging end of the associated equalizer being diagrammatically indicated at 10 in dot and dash lines. The jaws 8 are formed as downward extensions from the ends of the flanges 3 and 4 connected at their lower portions by upright transverse webs 11 and outstanding horizontal webs 12 at the lower ends thereof.

It will therefore be seen that said jaws 90 comprise transversely spaced flange or web portions 13 which are virtually extensions of the flange portions 3 and 4, spaced by the webs 6, 11 and 12. The adjacent edges of the webs 13 may be and are desirably rigidified by upright ribs 14.

In order to strengthen the pedestal 2, and particularly the junctions between the depending jaws 8 and the connecting flanges 3 and 4, I provide an outstanding rib or 100

flange 15 which preferably extends along the entire lower outside edge of the flange 4 and curves downwardly around the corners 16 between the flange 4 and the jaw webs 13 and extends diagonally downwardly and outwardly along said webs 13 to finally merge therewith along the back face of the pedestal. The front face of the pedestal is desirably reinforced in a similar manner by a rib or outstanding flange 17 which extends along the lower outer edge of the flange 3, curves downwardly around the corners 16 between said flange 3 and the webs 13 and extends downwardly, tapering and merging into the outer surface of the web 13 of the jaws. It will be clear that such a construction greatly strengthens the connection between the jaws and the connecting flanges 3 and 4 without substantially increasing the weight of the pedestal.

In order to greatly increase the life of the pedestal, renewable wear plates 18 are desirably employed, said wear plates being preferably generally U-shape in cross section, presenting the web portions 19 toward each other and with the flange portions 20 extending longitudinally away from each other and embracing the jaws and more particularly the flange portions 13 thereof. The flange portions 20 of the wear plates preferably taper toward their vertical mid-section, as indicated at 21, and are connected to the adjacent webs 13 by rivets or other connecting means 22, passing through registering apertures in the flanges 20 and the flanges 13. By having a rivet or the like connecting each flange 20 and the associated flange 13 a certain amount of material is saved as compared with using through connecting means. In order to rigidify the construction, the outer faces of the webs 13 are preferably ribbed or increased in thickness, as indicated at 23, along the inner or wear plate engaging sides thereof, said ribbed portions being extended to form bosses 24 through which the connecting means 22 passes.

In accordance with general practice the webs 11 only extend part way toward the flanges 3 and 4, leaving apertures 25 for receiving the equalizer 10. The wear or liner plate 18 is similarly formed in this respect. When assembled the flanges 26 on the journal box 9 extend on either side of the wear plates 18 and guide the journal box for vertical movement, as will be understood.

From the foregoing it will be seen that I have devised a truck pedestal which is conveniently formed by casting and adequately reinforced at the critical points against breakage. The life of said pedestal is greatly increased by using replaceable wear or liner plates therewith, which plates are desirably formed U-shape in section with outwardly extending flanges embracing the

associated edges of the pedestal and riveted thereto.

Having thus described my invention, I claim:

1. A pedestal for connection with a railway truck comprising a connecting portion and a pair of jaws spaced to receive an associated journal box therebetween, the corners at the union of said jaws and the connecting portion being reinforced by an outstanding rib on the inner and outer surfaces of said pedestal.

2. A pedestal adapted for connection with a railway truck comprising a connecting portion and a pair of jaws spaced to receive an associated journal box therebetween, the union of said jaws with said connecting portion being reinforced by an outstanding rib extending along the lower edge of said connecting portion, curved around the corners where the jaws connect thereto and extended part way along said jaws with the lower ends tapering in depth to gradually merge into said jaws.

3. A pedestal comprising a horizontal U-shaped portion adapted to embrace and be connected with the side frame of a railway truck and a pair of jaws extending downwardly from the ends of said U-shaped portion and spaced to receive an associated journal box therebetween, the union of said jaws and said connecting portion being reinforced by an outstanding rib along the lower edge of the connecting portion with the ends thereof bent downwardly, extended along the jaws, and tapering to finally merge therewith.

4. A pedestal comprising upstanding flanges adapted to embrace and be connected with the side frame of a railway truck the outer portions of said flanges being extended downwardly to form a pair of jaws spaced to receive an associated journal box therebetween, the inside edges of said connecting flanges and jaws being reinforced by outstanding ribs on the inner and outer surfaces of said pedestal along the lower edges of said flanges and continued at an angle thereto around the corners of the pedestal along the depending jaw portions.

5. A pedestal for connection with a railway truck comprising a connecting portion and a pair of jaws each comprising adjacent webs and outstanding flanges, and spaced to receive an associated journal box therebetween, wear plates U-shaped in section with outwardly extending flanges embracing the associated jaws and connected thereto, and separate means for connecting each flange of each wear plate to the corresponding flange of a jaw.

6. A pedestal adapted for connection with a railway truck comprising a connecting portion and a pair of jaws spaced to receive an associated journal box there-

between, and liner plates formed with web portions normally abutting the inner faces of said jaws and with outstanding flanges embracing the associated jaws and formed with free edges sloping outwardly and toward each other from the upper and lower portions thereof and connected thereto by separate means passing through the portion of each flange adjacent the union of said sloping edges and the corresponding portion of a jaw.

7. A pedestal comprising a horizontal U-shaped portion adapted to embrace and be connected with the side frame of a railway truck and a pair of jaws extending downwardly from the ends of said U-shaped portion and spaced to receive an associated journal box therebetween, the union of said jaws and said connecting portion being reinforced by an outstanding rib along the lower edge of the connecting portion with the ends thereof bent downwardly, extended along the jaws and tapering to gradually merge therewith, and wear plates embracing and attached to those portions of said jaws below said rib.

8. A pedestal comprising upstanding flanges adapted to embrace and be connected with the side frame of a railway truck, the outer portions of said flanges being extended downwardly to form a pair of jaws spaced to receive an associated journal box therebetween, and U-shaped wear plates with webs engaging the adjacent jaw faces and flanges extending away from each other on either side of said jaws and each flange separately connected to the adjacent flange of the associated jaw.

In testimony whereof I affix my signature.
